FRANK P. TOWNSEND, OF ELYRIA, OHIO, ASSIGNOR TO THE CUTLER-HAMMER MANUFACTURING COMPANY, OF MILWAUKEE, WISCONSIN, A CORPORATION OF WISCONSIN.

MOTOR-CONTROLLER.

No. 910,098.

Specification of Letters Patent.

Patented Jan. 19, 1909.

Application filed July 16, 1906. Serial No. 326,468.

To all whom it may concern:

Be it known that I, FRANK P. TOWNSEND, a citizen of the United States, residing at Elyria, in the county of Lorain and State 5 of Ohio, have invented new and useful Improvements in Motor-Controllers, of which the following is a full, clear, concise, and exact description, reference being had to the accompanying drawing, forming a part of 10 this specification.

My invention relates to improvements in motor controllers.

It provides apparatus which is particularly adapted to control and operate metal 15 rolling mills in which two tables for carrying a metal slab are arranged one upon each side of the working rolls which operate upon the slab. Each table is provided with carrying rolls which are driven to pass the slab 20 back and forth through the working rolls. In order to distinguish the tables from each other, I shall designate one the right table and the other the left table.

When the mill is in operation, the slab is 25 passed from the right table through the working rolls to the left table, then from the left table through the working rolls to the right table, and so on back and forth through the working rolls from one table to the other 30 until it is brought into the proper form. When either table feeds the slab to the working rolls, it runs in the forward direction, and when either table draws the slab from the working rolls it runs in the reverse direction. It has been the practice heretofore 35 to operate both tables simultaneously, one being operated in the forward direction and the other in the reverse direction, so that one table feeds the slab to the working rolls 40 while the other table draws it therefrom.

According to my invention, the tables are run alternately in the forward direction without operating either table in the reverse direction, save when the slab will not pass 45 entirely through the rolls unless it is drawn out by the table onto which it is being passed. I am thus enabled to operate a rolling mill on less power than has heretofore been consumed, and, furthermore, I 50 save wear upon the machinery.

In accordance with the preferred form of my invention, I employ two motors to drive the tables, one motor being provided for each table. The motors are so connected to 55 the tables that both the motors and the

tables are independent. The motors are preferably controlled by means of two automatic controllers, one for each motor. These controllers may assume any suitable form. Both controllers are preferably controlled 60 by means of a single master controller which the operator or attendant may operate at will to cause such operation of the motors as may be required. The controlling apparatus which I thus provide is adapted to 65 be so operated that it will cause the motors, and, consequently, the tables to operate alternately in the forward direction, while allowing either table to remain idle while the other is in operation. I preferably provide 70 the controlling apparatus with means by which either motor, and, consequently, either table, may be run in the reverse direction, if an occasion should arise to require such operation. It will, of course, be understood 75 that my controlling apparatus may assume various forms, and that it may be used for purposes other than those which I particularly set forth. Furthermore, certain features of my invention are applicable to vari- 80 ous forms of apparatus.

In order to more particularly explain the nature of my invention, I have illustrated a rolling mill and controlling apparatus wherein my invention is embodied in one of 85 the forms that it may assume.

The several views in the accompanying drawings are as follows:

Figure 1 is a diagrammatic plan view of a rolling mill and the motors which are employed to operate the tables, Fig. 2 is a diagrammatic view of the controlling apparatus for the motors, Fig. 3 is a diagrammatic view of an automatic multiple switch motor controller which may be used in the 90 controlling apparatus, and Fig. 4 is a diagrammatic plan of the drum of the master controller. 95

Fig. 1 shows one form of rolling mill which my system may be employed to operate. It is provided with two tables A and B, between which are arranged working rolls 1. Each table is provided with a set of carrying rolls 3, which are geared to a shaft 4. Each table may be mounted upon 100 bearings 5 so that it may be tilted.

I prefer to employ two motors A¹ and B¹ to operate the tables A and B respectively, the motor A¹ being geared to the shaft 4 of table A and the motor B¹ being geared to 110

the shaft 4 of table B. The motors A and B are preferably mounted in substantially the same way as railway motors.

I shall first describe the controlling apparatus which is illustrated in Fig. 2. I employ two sets of controlling apparatus A¹, B², the set A¹ being employed to control the motor A¹ and the set B² being employed to control the motor B¹. Each set of controlling apparatus may be provided with an automatic rheostat and a reversing switch. Both sets of controlling apparatus are controlled by means of a master controller M. Fig. 4 is a diagrammatic plan view of the drum of the master controller. It will, of course, be understood that the master controller may assume various forms.

I shall now describe the operation of the controlling apparatus. The master controller may be provided with stationary contact fingers 6, 7, 8, 9, 10, 11, and 12. The left hand side of the drum of the master controller may be provided with segments 13, 14, 15, 16, and 17, and the right hand side thereof may be provided with segments 18, 19, 20, 21, and 22. It may be assumed that the master controller is moved so that the left hand segments come into engagement with the contact fingers. When the contact fingers reach the position 1^A, circuit will be closed from the positive line through conductor 23, finger 12, segment 17, segment 16, finger 11, conductor 24, reversing switch solenoid 25, conductor 26, and conductor 27 to the negative line. The solenoid 25 will then close the reversing switch, thereby closing the motor circuit from the positive line through field 28, conductor 29, contact 30, conductor 31, armature 32, conductor 33, contact 34, conductor 35, starting resistance 36, contact arm 37 and conductor 27 to the negative side of the line. The motor will thus be started with all the starting resistance in circuit. When the contact fingers reach the position 2^A, circuit will be closed from the positive line through conductor 23, segment 17, segment 15, finger 9, conductor 38, rheostat solenoid 39, to the negative side of the line. The solenoid 39 will then raise the contact arm 37, causing it to pass over contacts 40 to remove the starting resistance from circuit. The movement of the contact arm will be retarded by the dash-pot 41. The motor A¹ will thus be started and drive the left hand table in a forward direction so as to feed the slab to the working rolls. If it be desired to run the table B in a reverse direction so that it will draw the slab from the working rolls, the motor B¹ may be started in the reverse direction by further moving the master controller to bring the contact fingers into the positions 3^B and 4^B. When the contact fingers reach the third position, circuit will be closed from the positive line through the

conductor 23, finger 12, segment 17, segment 14, finger 7, conductor 42, reversing switch solenoid 43, conductor 44, and conductor 45 to the negative side of the line. The solenoid 43 will then close the reversing switch 70 of the controlling apparatus B², thereby closing the circuit of the motor B¹ from the positive line, through series field 46, conductor 47, conductor 48, contact 49, conductor 50, armature 51, conductor 52, contact 53, 75 conductor 54, starting resistance 55, arm 56 and conductor 45 to the negative side of the line. The motor B¹ will thus be started in the reverse direction with all the starting resistance 55 in circuit. When the contact fingers reach the position 4^B, circuit will be closed from the positive line through conductor 23, finger 12, segment 17, segment 13, finger 6, conductor 57, rheostat solenoid 58, and conductor 45 to the negative side of the 85 line. The solenoid 58 will then move the contact arm 56 over the contacts 59 to remove the starting resistance from circuit. The movement of the contact arm 56 will be retarded by the dash-pot 60. The motor 90 B¹ will thus be started and drive the table B in the reverse direction so as to draw the slab from the working rolls.

In order to stop tables A and B the handle of the master controller is returned to its 95 initial position. The controlling circuits of the motor controllers are thus opened and consequently the motors A¹ and B² are stopped.

In order to feed the slab back to the working rolls from table B, the master controller is turned so as to bring the right hand segments into engagement with the contact fingers. When the contact fingers reach the position 1^B, circuit will be closed from the positive line through conductor 23, finger 12, segment 22, segment 19, finger 8, conductor 61, reversing switch solenoid 62, conductor 44, and conductor 45 to the negative side of the line. The reversing switch will then 105 close the motor circuit from the positive line through series field 46, conductor 47, contact 63, conductor 52, armature 51, conductor 50, contact 64, conductor 54, starting resistance 55, arm 56, and conductor 45 to the negative side of the line. When the contact fingers reach the position 2^B, circuit will be closed from the positive line through conductor 23, finger 12, segment 22, segment 18, finger 6, conductor 57, rheostat solenoid 58, 115 and conductor 45 to the negative side of the line. The solenoid 58 will then move the contact arm 56 over the contacts 59 to remove the starting resistance 55 from circuit. The motor B¹ will thus be started and drive 125 the table B in the forward direction so as to feed the slab to the working rolls 1.

If it be desired to run the table A in a reverse direction so as to draw the slab from the working rolls, the master controller may 130

be turned further so as to bring the contact fingers into the positions 3^A and 4^A. When the contact fingers reach the position 3^A, circuit will be closed from the positive line 5 through the conductor 23, finger 12, segment 22, segment 21, finger 10, conductor 65, solenoid 66, conductor 26 and conductor 27 to the negative line. The solenoid 66 will then close the reversing switch of the controlling 10 apparatus A², thereby closing the circuit to the motor A¹ from the positive line through field 28, conductor 29, conductor 67, contact 68, conductor 33, armature 32, conductor 31, contact 69, conductor 35, resistance 36, arm 15 37, and conductor 27 to the negative line. When the contact fingers reach the position 4^A, circuit will be closed from the positive line through conductor 23, finger 12, segment 22, segment 20, finger 9, conductor 38, 20 rheostat solenoid 39, and conductor 27 to the negative line. The solenoid 39 will then draw the contact arm 37 over the contacts 40 to remove the starting resistance 36 from circuit. The motor A¹ will thus be started 25 in the reverse direction and drive the table A accordingly. The operation of the motors may thus be directed through the agency of a single master controller so that the tables are operated alternately in the forward 30 direction to send the slab back and forth through the working rolls. Inasmuch as neither table need be operated in the reverse direction save when it is necessary to draw the slab from the working rolls, considerable 35 power is saved in operating the mill. It will, of course, be understood that various forms of controlling apparatus may be employed for the motors. The apparatus which I have illustrated has been selected merely 40 for the purpose of explaining the general features of my invention.

The multiple switch starter which is illustrated in Fig. 3 is especially adapted for starting large motors, such as are employed 45 for operating rolling mills. It is provided with a plurality of accelerating switches *a*, *a*¹, *a*², and *a*³, which are operated by solenoids, *b*, *b*¹, *b*² and *b*³, respectively. The accelerating switches carry auxiliary switches 50 *c*, *c*¹, *c*², and *c*³, respectively. The sections of starting resistance *d*, *d*¹, *d*², and *d*³, are arranged to be short-circuited by the accelerating switches *a*, *a*¹, *a*², and *a*³ respectively. The solenoids *b*, *b*¹, *b*², and *b*³ may be connected 55 to the conductor 38 which extends from the contact finger 9 of the master controller. The circuits of these solenoids are so arranged that when the solenoid *b* closes the accelerating switch *a*, the auxiliary 60 switch *c* closes the circuit to the solenoid *b*¹; when the solenoid *b*¹ closes the switch *a*¹, the auxiliary switch *c*¹ closes the circuit to the solenoid *b*²; and when the solenoid *b*² closes switch *a*², the auxiliary switch *c*² closes the 65 circuit of the solenoid *b*³. These solenoids

are thus made to respond successively so that the accelerating switches will be closed one after another to remove the sections of starting resistance from circuit one by one. In order that the solenoids will not respond in too rapid succession, I provide an arresting device which is responsive to the motor current. The arresting device is provided with a plurality of relay switches *e*, *e*¹, *e*², and *e*³ which are arranged one in the 70 circuit of each of the solenoids *b*, *b*¹, *b*², and *b*³. These relay switches are connected to the core of a relay solenoid *f*, which is arranged in circuit in series with the armature of the motor A¹. The reversing switch is 75 provided with switches *g*, *g*¹, *g*², and *g*³, which are operated by solenoids *h*, *h*¹, *h*², and *h*³ respectively. The solenoids *h* and *h*¹ are connected to the conductor 24 which is connected to the contact finger 11 of the 80 master controller. The solenoids *h*² and *h*³ are connected to the conductor 65 which is connected to contact finger 10 of the master controller.

I have illustrated the multiple switch controller as it would be arranged if it were used in place of the controlling apparatus A² which is shown in Fig. 2. I shall now describe the operation of the multiple switch controller. Assuming that the 90 master controller be moved so that the left hand contact segments engage the contact fingers, circuit is first closed from conductor 24, through solenoids *h* and *h*¹, conductor 70, conductor 71, and conductor 72 100 to the negative side of the line. The solenoids *h* and *h*¹ then close the switches *g* and *g*¹ and the motor circuit will be closed from the positive line through field 28, conductor 73, conductor 74, switch *g*, conductor 75, 105 armature 32, conductor 76, conductor 77, switch *g*¹, conductor 78, relay solenoid *f*, resistance *d*³, *d*², *d*¹, and *d*, and conductor 79 to the negative side of the line. The motor will thus be started with all the starting 110 resistance in circuit. When the contact fingers reach the position 2^A, circuit will be closed from conductor 38 through conductor 80, solenoid *b*, conductor 81, relay switch *e*, and conductor 72 to the negative side of the 115 line. The accelerating switch *a* will then be closed and short-circuit the section of starting resistance *d*. The auxiliary switch *c* will also be closed, thereby closing the circuit of solenoid *b*, around relay switch *e*, 120 through auxiliary switch *c*, accelerating switch *a*, and conductor 79. The relay switch will thus be short-circuited and, therefore, it may be opened without de-energizing the solenoid *b*. The auxiliary switch *c* will 125 close a circuit from the conductor 38 through conductor 80, solenoid *b*¹, conductor 82, relay switch *e*¹, conductor 83, auxiliary switch *c*, accelerating switch *a*, and conductor 79 to the negative side of the line. The accelerat- 130

ing switch a^1 and the auxiliary switch c^1 will then be closed by the solenoid b^1 . The section d^1 of the starting resistance will then be short-circuited by the accelerating switch a^1 . If the motor current rises to a certain degree after the section of starting resistance d is removed from circuit, the relay solenoid f will open the relay switches e , e^1 , e^2 , and e^3 . In consequence the operation 5 of the succeeding accelerating switches will be arrested, as the circuits of the solenoids thereof will be opened by the relay switches. As soon as the motor current decreases the relay solenoid will allow the relay switches 10 to close, and then the solenoid b^1 will respond and close the switch a^1 . Inasmuch as the auxiliary switch c short-circuits the relay switch e , said relay switch may be opened without deenergizing the winding b . The auxiliary switch c^2 serves to close the circuit 15 of the solenoid b^2 and also short circuit the relay switch e^2 and the auxiliary switch c^3 serves to short-circuit the relay switch e^3 . Without following out the operation of each 20 switch in detail, it will be understood that the accelerating switches are closed successively to remove the sections of starting resistance from circuit one by one and that if the motor current becomes too great, the relay solenoid f will open the relay switches 25 to arrest the operation of the accelerating switches until the motor current subsides.

The motor will be operated in the reverse direction if the master controller be moved 30 so that the right hand contact segments engage the contact fingers. When the contact fingers reach the position 3^A , circuit will be closed from the conductor 65 through solenoids b^2 and b^3 to conductor 71. The 35 motor circuit will then be closed from the positive line through field 28, conductor 73, switch g^2 , conductor 76, armature 32, conductor 75, switch g^3 to the relay switch f . When the contact fingers reach the position 40 4^A , circuit will be closed from the conductor 38, thence through the solenoids b , b^1 , b^2 , and b^3 , as previously described, and accordingly the accelerating switches will be closed successively to remove the starting resistance 45 from circuit.

It will be understood that my invention in its broadest aspect is not limited in any way to the details which I have particularly set forth herein in explaining the apparatus 50 which I have illustrated.

In order to enable me to clearly set forth my invention in the claims, I have specified two motors. I intend, however, that my claims shall comprehend instances where 55 more than two motors are controlled in the manner contemplated by my invention.

Having thus described my invention, what I claim and desire to secure by Letters Patent is,

65 1. In combination, two motive power de-

vices and controlling apparatus by means of which the operation of said devices may be directed so that said devices may be run either alternately in opposite directions or simultaneously in one direction.

2. In combination, a rolling mill having two tables for carrying the work and passing it back and forth through the working rolls, two motive power devices, one for each table, and controlling apparatus by 70 means of which the operation of said devices may be so directed that said devices may be run either alternately or simultaneously at will.

3. In combination, two electric motors and 80 controlling apparatus by means of which the operation of said motors may be so directed that the same may be run either alternately in opposite directions or simultaneously in one direction.

4. In combination, two electric motors and controlling apparatus by means of which the operation of said motors may be so directed that the same may be run either alternately in the forward direction, or simultaneously, one in the forward direction and 90 the other in the reverse direction.

5. In combination, a rolling mill having two tables for carrying the work and passing it back and forth through the working 95 rolls, two electric motors, one for each table for operating said tables, and controlling apparatus by means of which the operation of said motors may be so directed that said motors may be run either alternately or simultaneously.

6. In combination, a rolling mill having two tables for carrying the work and passing it back and forth through the working rolls, two motors, one for each table, for driving 105 said tables, and controlling apparatus by means of which the operation of said motors may be so directed that the same may be run either alternately in the forward direction, or simultaneously, one in the forward 110 direction and the other in the reverse direction.

7. In combination, two motive power devices, a controlling device for each motive power device, and a master controller for 115 said controlling devices by means of which said motive power devices may be caused to run either alternately or simultaneously at will.

8. In combination, two motive power devices, two controlling devices, one for each motive power device, and a master controller for said controlling devices by means of which the operation of said controlling devices may be so directed that said motive 125 power devices will be caused to run either alternately in the forward direction or simultaneously, one in the forward direction and the other in the reverse direction.

9. In combination, a rolling mill having 130

two tables for carrying the work and passing it back and forth through the working rolls, two motive power devices, one for each table, for driving said tables, a controlling device for each motive power device, a master controller for said controlling devices by means of which said controlling devices may be operated to cause said motive power devices to run said tables either alternately or simultaneously.

10. In combination, a rolling mill having two tables for carrying the work and passing it back and forth through the working rolls, two motive power devices, one for each table, for driving said tables, controlling devices, one for each motive power device, and a master controller for said controlling devices by means of which said controlling devices may be operated so as to cause said motive power devices to drive said tables either alternately in the forward direction or simultaneously, one in the forward direction and the other in the reverse direction.

11. In combination, two electric motors, two controlling devices, one for each motor, and a master controller for said controlling devices by means of which said motors may be caused to run either alternately or simultaneously at will.

12. In combination, two electric motors, two controlling devices, one for each motor, and a master controller for said controlling devices by means of which said motors may be caused to run either alternately in the forward direction, or simultaneously, one in the forward direction and the other in the reverse direction.

13. In combination, a rolling mill having two tables for carrying the work and passing it back and forth through the working rolls, two motors one for each table for driving said tables, two controlling devices, one for each motor, and a master controller for said controlling devices by means of which said motors may be caused to drive said tables either alternately in the forward direction, or simultaneously, one in the forward direction and the other in the reverse direction.

14. In combination, two motors, a controlling device for each motor having an automatic rheostat and a reverse switch, and a master controller for said controlling devices by means of which the operation of said controlling devices may be directed so as to cause said motors to run either alternately or simultaneously.

15. In combination, two electric motors, a controlling device for each motor having an automatic rheostat and a reversing switch, and a master controller for said controlling devices by means of which the operation of said controlling devices may be directed so as to cause said motors to run either alternately in the forward direction or simulta-

neously, one in the forward direction and the other in the reverse direction.

16. In combination, two electric motors, a controlling device for each motor having an automatic rheostat and a reversing switch, and a master controller for said controlling devices by means of which the operation of said controlling devices may be so directed that the first motor may be run in the forward direction alone, and then both motors run simultaneously, the first in the forward direction and the second in the reverse direction, or the second motor may be run alone and then both motors run simultaneously, the second in the forward direction and the first in the reverse direction.

17. In combination, two motors, a controlling device for each motor having an automatic multiple switch starter and a reversing switch, and a master controller by means of which the operation of said controlling devices may be so directed that the motors may be run either alternately in the forward direction, or simultaneously, one in the forward direction and the other in the reverse direction.

18. In combination, a rolling mill having two working tables for carrying the work and passing it back and forth through the working rolls, two electric motors, one for each table, for driving said tables, two controlling devices, one for each motor, having a magnetically operated reversing switch and a magnetically operated rheostat, and a master controller for said controlling devices by means of which the operation of both controllers may be so directed that the motors may be caused to drive said tables either alternately in the forward direction or simultaneously, one in the forward direction and the other in the reverse direction.

19. In combination, a rolling mill having two working tables for carrying the work and passing it back and forth through the working rolls, two electric motors, one for each table, for driving said tables, two controlling devices, one for each motor, each having a magnetically operated reversing switch, and a magnetically operated rheostat, and a master controller for said controlling devices by means of which the operation of both controllers may be so directed that the motors may be caused to drive said tables either alternately in the forward direction or simultaneously, one in the forward direction and the other in the reverse direction, said master controller being adapted to make the simultaneous operation of said tables take place after either table has been operated alone.

20. In combination, a rolling mill having two working tables adapted to carry the work and pass it back and forth through the working rolls, two motors, one for each table, for driving said tables, two control-

ling devices, one for each motor, each having a magnetically operated multiple switch rheostat and a magnetically operated reversing switch, and a master controller by means of which the operation of said controlling devices may be so directed that the motors may be caused to drive the tables either alternately in the forward direction, or simultaneously, one in the forward direction and the other in the reverse direction.

21. In combination, a rolling mill having two tables adapted to carry the work and pass it back and forth through the working rolls, two motors, one for each table, for driving said tables, two controlling devices, one for each motor, each having a magnetically-operated multiple switch rheostat and a magnetically-operated reversing switch,

and a master controller by means of which the operation of said controlling devices may be so directed that the motors may be caused to drive the tables either alternately in the forward direction, or simultaneously, one in the forward direction, and the other in the reverse direction, said master controller being adapted to make the simultaneous operation of said tables take place after either table has been operated alone.

In witness whereof, I have hereunto subscribed my name in the presence of two witnesses.

FRANK P. TOWNSEND.
